DESIGN FOR A COMBINATION BROILER AND COOKER

Harold T. Austin, Seattle, Wash.

Application November 18, 1941, Serial No. 104,192

Term of patent 14 years

To all whom it may concern:

Be it known that I, Harold T. Austin, a citizen of the United States, residing at Seattle, in the county of King, State of Washington, have invented a new, original, and ornamental Design for a Combination Broiler and Cooker, of which the following is a specification, reference being had to the accompanying drawing, forming part thereof.

Figure 1 is an elevational view of the combination broiler and cooker, showing my design;

Figure 2 is an elevational view taken at a right angle to the view shown in Figure 1; and

Figure 3 is a top plan view thereof.

I claim:

The ornamental design for a combination broiler and cooker, substantially as shown.

HAROLD T. AUSTIN,
